UNITED STATES PATENT OFFICE.

FOREST V. DETWILER, OF POTTSTOWN, PENNSYLVANIA.

HYDROCARBON-BURNER.

1,303,866.

Specification of Letters Patent. Patented May 20, 1919.

Application filed October 19, 1917. Serial No. 197,434.

To all whom it may concern:

Be it known that I, FOREST V. DETWILER, a citizen of the United States, residing at Pottstown, in the county of Montgomery and State of Pennsylvania, have invented 5 certain new and useful Improvements in Hydrocarbon-Burners, of which the following is a specification.

This invention relates to improvements 10 in hydrocarbon burners and one of the objects of the same is to improve and simplify the construction of burners of this character whereby the cost of manufacture will be materially reduced and at the same 15 time the efficiency of the burner will be greatly increased.

A further object is to provide an improved 20 burner of this character whereby a perfect blue flame will be produced with hydrocarbon oil, without the slightest noise or pulsation, such as is common in hydrocarbon burners heretofore constructed.

A further object is to provide an improved 25 burner of this character which will be of a sectional construction embodying separate units whereby a burner of any desired size may be built up without necessitating special patterns for the different sizes of burners.

30 A still further object is to provide a burner of sectional construction, portions of the sections of which are so shaped in the manufacture thereof as to form portions of the gas discharge slots, whereby the 35 laborious operation of cutting these slots in the completed burners, in the manner in which they have heretofore been constructed, will be obviated.

To the attainment of these ends and the 40 accomplishment of other new and useful objects as will appear, the invention consists in the features of novelty in substantially the construction, combination and arrangement of the several parts hereinafter 45 more fully described and claimed, and shown in the accompanying drawings, illustrating the invention, and in which:

Figure 1 is a view partly in elevation and 50 partly in vertical section of an improved burner of this character, constructed in accordance with the principles of this invention.

Fig. 2 is a view in horizontal section as taken on line 2—2, Fig. 1.

Fig. 3 is a detail view in elevation of a 55 portion of the body of the burner.

Fig. 4 is a vertical longitudinal sectional view of a modified form of the burner.

Fig. 5 is a top plan view partly in horizontal section of the form shown in Fig. 4. 60

Fig. 6 is a top plan view of the priming cup.

Fig. 7 is a vertical sectional view taken on line 7—7, Fig. 4.

Fig. 8 is a front elevation of one of the 65 units, constituting the body of the burner.

Fig. 9 is a detail view in elevation of several of the units forming the body portion of the burner.

Fig. 10 is a view taken on line 10—10, 70 Fig. 11.

Fig. 11 is a side elevation partly in section of the parts shown in Fig. 10.

Fig. 12 is a vertical sectional view of the body portion of another modified form of 75 the invention.

Fig. 13 is a top plan view of one of the units constituting the body portion of the burner shown in Fig. 12.

Referring more particularly to the drawing, and in the form of the invention shown in Figs. 1 to 3, the body of the burner is preferably of a frusto conical shape, comprising a plurality of superposed units 80 15 having an outer rim 16, and an annular central portion 17 and a plurality of ribs 18 connecting the central portion and the rim. The rim 16 is reduced at its upper portion to form a shoulder 19 upon which the lower edge of the next uppermost unit is adapted 90 to rest, and the said lower edge of each of the units is provided with cut-away or reduced portions 20, forming intermediate 95 projecting lugs 21 to rest upon the edges of the next adjacent unit, with the result that elongated narrow slots 22 will be formed about the body portion of the burner and between the adjacent units. The purpose 100 of these slots or openings 22 is to permit the gas or vapor and the flame of the burner to pass from the inside to the outside of the burner. The lower portion of this form of burner is formed of superposed elements 105 23, 24, which are of the same general construction as the remaining elements, but the element 23 is provided with a portion 25 which extends across the opening 26 formed by the superposed elements and this opening

constitutes a heating chamber which is adapted to be closed by the cap element 27, and which latter is also constructed to form the slots or openings 28. The element 24 5 is arranged below the element 23 and is provided with an opening 29 arranged centrally thereof and the superposed elements are all supported by a base 30, constituting the bottom of the burner body. The above mentioned parts are secured together by means 10 of fastening bolts 31 which pass through the top member 27 and the bottom member 30 and a nut 32 is provided on the bottom of the fastening bolt so that the parts may 15 be removably secured together. If desired a tubular member 33 may be provided which passes through a portion 33^a of each of the ribs 18 and surrounds the bolt 31. Any 20 number of these tubular members and fastening bolts may be provided and the members serve the function of preventing the hot gases in the chamber 34 formed by the superposed units from condensing before it is burned. The hot gases circulate around 25 these members 33 and heat the air which is in the chamber. A mixing chamber in the form of a pipe or flue 35 is supported in any suitable manner such as by means of supports 36 and one end thereof is turned upwardly as at 37 and enters a recess 38 in 30 the bottom member 30 of the burner in such a manner as to form a support for the burner body. The opening of the flue 35 registers with the opening 29 in the unit 24, 35 so that the gases will be discharged from the flue 35 against the portion 25 of the element 23 to circulate in the chamber 34 and to be discharged therefrom through the openings 22, 28.

40 The bottom of the body of the burner may be shaped to form an upwardly opening priming cup 39 which contains asbestos or any other suitable material 40. Suitable supporting brackets 41 may be provided for 45 supporting the generating pipe 42, which latter encompasses the body of the burner in proximity thereto, so that the flame from the burner will impinge the pipe. The fluid to be vaporized is supplied to the generating 50 pipe 42 from the supply pipe 43, connected to any suitable source of supply, and through the pipe 44 which discharges into one end of the generating pipe, from this generating pipe 42 the vapor passes through the 55 pipe 45 to the connection 46 and thence to the nozzle 47 which is located to discharge into the flue or passage 35 serving as an injector for the vaporized fluid to be burned, and this nozzle 47 is controlled by a suitable 60 needle valve 48.

If desired a priming cup 49 may be disposed beneath the nozzle 47 and supported in any suitable and convenient manner and another priming cup 50 may also be provided and supported in any convenient or

suitable manner so that it will stand beneath the pipes 44, 45 and preferably intermediate the body of the burner and the nozzle 47. Thus it will be seen that the oil being vaporized in the pipe 42 will be discharged 70 into the flue 35 and from there into the chamber 34 of the burner, contacting with the walls of the chamber 26 and also with the tubular members 33, during which time the gases will become thoroughly mixed 75 within the chamber 34 of the burner.

With this improved construction, it will be manifest that the size of the burner may be varied by adding any number of units 15 or by taking any number of units therefrom, according to the size of the burner 80 which it is desired to produce.

In the form shown in Figs. 4 to 9, the burner is of a substantially oblong construction, and is constructed of a plurality of units 51, constructed in the same manner as the units 15, with the exception that all of the units 51 are of a uniform size, but are so shaped that they will produce the narrow slots or openings 52 through which the gas is discharged from the chamber in the body of the burner. Each of these units 51 is provided with ribs 53 to form spaces 54 therebetween, and when assembled, the units will 90 form the chamber 55^a from which the gas is discharged through the openings 52 and which openings are formed by means of the lugs or projections 55. In this form of burner, there is provided the central unit 56 on each side of which the units 51 are 95 arranged and each edge of the unit 56 is provided with a shouldered portion 57 to receive the lugs or projections 55. End members 58 are provided which are arranged on 100 each side of the central member 56 and adjacent the outermost unit 51, and these end members are provided with portions 59 which form closures for the chamber 54. The units 51, central member 56 and end members 59 are detachably secured together 105 in any suitable manner preferably by means of a fastening rod or bolt 60, which passes through apertures 61 in ears 62 on each of the units 51 and corresponding ears 63, 64 respectively on the central and end members 110 56, 59. Corresponding ears 65 are provided on the elements 51 through which a fastening bolt or rod 66 passes and this bolt 66 passes through an ear 67 on the end member 59 and has threaded engagement 68 115 with a portion of the central member 56. Thus it will be seen that when it is desired to alter the length of the form of burner shown in Fig. 4, or manufacture a burner of a different length, all that is necessary is 120 to vary the number of units 51.

Each of the units 51 is provided with an annular central portion 69 which registers with a corresponding annular portion 70 of the central unit 56 to form a chamber 71, 125

which chamber is closed by suitable end members 72, having an opening 73 therethrough and through which opening a pipe 74 passes. To the end 75 of this pipe 74 is connected the supply pipe 76 so that the oil to be vaporized which flows into the pipe 76 from any suitable source will pass into the pipe 74, to flow through the chamber 71 and from there to the pipe 77 through a suitable connection 78, to be conducted by the pipe 77 which is arranged exterior of and adjacent to the body of the burner so that it will be heated by the flame coming from the slots or openings 52. From the pipe 77, the vapor will flow into the pipe 78 and thence into the pipe 79, which latter pipe is also arranged adjacent the body of the burner to be impinged by the flame therefrom, and from this pipe 79, the vapor will pass to the pipe 80 and from thence to the nozzle 81, to be discharged into the pipe or flue 82, which latter discharges as at 83 into the chamber 54 within the body of the burner and which surrounds the inner chamber 71.

25 In order that the pipes 77, 79 may be supported and held in position, the end members 59 of the body of the burner may be provided with ears or projections 59^a, through which the respective pipes pass and 30 additional ears 56^a having apertures therethrough, through which the pipes 77, 79 pass, may be provided on the central unit or member 56.

The end of the pipe or flue 82 is connected 35 with the central member 56 of the body in any suitable or convenient manner and serves as a means for supporting the body. The pipe 82 is itself supported by suitable supports 84. A suitable priming cup 85 may 40 be provided beneath the nozzle 81 and a suitably supported priming cup 86 may be also provided so as to be disposed beneath the pipes 77, 79 and connection 78. In order that the priming cup may be held in position 45 and relieved of weight, suitable supports 86^a may be provided, the support at the forward end of the priming cup adjacent the supply pipe 76 may be provided with a cap 86^b, removably secured to the support 86^a in any 50 suitable manner such as by means of suitable fastening devices, and this cap 86^b may be provided with an upright portion having an opening therethrough and through which the supply pipe 76 passes, thereby serving as 55 a means for supporting the supply pipe.

Arranged within the priming cup 86 is a pipe 87 which is provided with suitable apertures 88 in the bottom thereof and the pipe may be covered with any suitable material such as asbestos or the like. The pipe 60 is supplied with fuel from the supply pipe 76 preferably by means of a connection 90 and a controlling valve 91 may be also provided, so that when it is desired to start the 65 burner, the controlling valve 91 may be

opened to permit oil to be discharged into the priming cup and then closed.

With this improved construction, it will be manifest that as the oil comes from the source of supply and flows through the pipe 76, it is in a practically cold state and passes along the under side of the burner into the pipe 74, that is located within the heating chamber 71. This heating chamber raises the temperature of the oil to practically a 75 boiling point so that the oil is at a high boiling temperature when it passes from the pipe 74 into the connection 78 and from there into the pipe 77. The pipe 77 being enveloped in the flame, reduces to a certain degree carbonization, by having the oil at a high degree of heat before coming into contact with the pipe that is heated to a considerably higher degree of heat than the pipe 74. Heretofore introducing the hydrocarbon oil 80 into a pipe at a very high degree of heat has a tendency to carbonize the oil, but with this improved construction, this objection is eliminated to a great extent, and the burner 85 may be used for a considerable length of 90 time before it is necessary that it be cleaned.

After the hydrocarbon oil has passed through the pipe 77, it is in a highly vaporized state and passes to the connection 78, from there to the pipe 79 and from the pipe 95 79 through the connection 80 to the nozzle 81 to be discharged therefrom at a very high temperature into the flue or pipe 82, where it is mixed with the air and is carried to the burner into the chamber 54 where it is 100 ignited. The chamber 71 through which the pipe 74 passes and which is formed by the assembling of the units 51, constitutes the heating chamber for raising the temperature of the oil before it flows into the pipe 77. 105 The walls of this chamber also serve as a hot gas chamber on the outside, giving the gas a chance to thoroughly mix with the air before it is ignited on the outside of the burner. Without this inner chamber 71, it 110 has been found that the gas in the chamber 54 will "back fire" or ignite at the needle valve. In order that the pipes may be readily cleaned when desired, the couplings between the pipes may be provided with 115 screw plugs 92 which may be removed to permit access to the interior of the pipes.

In the form of the burner shown in Figs. 10 and 11, the units 93 constituting the body of the burner are provided with the lugs 94 120 to form the slots or openings 95, and if desired, the alternate units 96, may be of uniform height throughout so that the lugs 94 will be formed only on the units 93. In this form of the invention a unit 97 is provided 125 which may be arranged in any position with respect to the remaining units and has formed integral therewith the generating pipe 98 which surrounds the outside of the unit. To one end of this generating pipe 98 is con- 130

nnected the supply pipe 99, having a controlling valve 100 therein for controlling the supply of oil which flows to the pipe 99 through the pipe 101 which latter receives its supply 5 from a suitable tank 102. To the other end of the generating pipe 98 is connected an outlet pipe 103 to which is connected the nozzle 104 by means of the connection 105. The nozzle 104 discharges into the pipe or flue 106 which 10 in turn discharges into the body of the burner in the manner shown in Figs. 1 and 4. Oil is supplied to the priming cup 107 located beneath the generating pipe 98 and to the priming cups 108, 109 in any suitable 15 manner, preferably by the respective nozzles 110, 111, 112, which are connected with the pipe 113, the latter in turn being connected by means of a suitable connection 114 with the pipe 99, and a suitable controlling valve 20 115 may be provided for controlling the supply of oil to the pipe 113. Thus in order to start the burner, and when it is desired to supply oil to the priming cups, the valve 115 is opened and when sufficient oil has been 25 discharged into the priming cups, the valve is closed. The generating pipe 98 being located outside of the body of the burner will be in a position to be impinged by the flame from the burner and vapor will be generated 30 in this pipe in the same manner as in the form shown in Fig. 1.

Referring to the form of the invention shown in Figs. 12 and 13, the units comprising the body portion embody an annular 35 portion 116 within which is arranged a concentric annular portion 117 of a diameter somewhat smaller than the diameter of the portion 116. A circumferential flange 118 is connected with the outer periphery of the 40 annular portion 117 and the diameter of this flange is somewhat less than the internal diameter of the annular portion 116, so that the ribs 119 which project from the periphery of the circumferential flange 118 will 45 form spaces 120 between the ribs and between the periphery of the flange 118 and the annular portion 116. The flange 118 is provided with perpendicularly arranged portions 121, extending entirely around and 50 adjacent the periphery of the flange and on each side thereof, so that when the units are assembled there will be formed dead air chambers 122 between the portions 121 and the annular portion 117 of each unit. The 55 surface of the portion 117 is shouldered as at 123 so that the inner portions of the units will interlock, while the ribs 119 adjacent the annular member 116 are provided with projections 124 to form slightly depressed 60 portions 125 intermediate the projections so that when the units are assembled and fastened together by means of the fastening bolts 126, the portions 125 of the units will form the slots or narrow openings arranged 65 horizontally at the periphery of the body of

the burner to permit the gas to pass there-through.

The bottom member 126 of the unit is provided with a priming cup 127, and an opening 128 into which opening the end of the 70 tube 35 projects so as to support the burner. When the units are assembled, the cap member 129 forms a closure for the chamber 120 formed by the spaces between the ribs 119 and the inner annular portion 117 of the 75 units coöperate to form an intermediate chamber across which chamber and preferably adjacent the bottom thereof is arranged a reticulated member or screen 130 so as to prevent the gases from lighting back to the 80 nozzle.

With this form of the invention, it will be noted that the flanges 118 and the perpendicularly arranged portion 121, together with the inner annular portions 117, co-operate to form the dead heat chamber which is disposed between the chamber 131 and the chamber 120 so that the gases entering the burner will pass through the reticulated member 130 into the chamber 131 to be discharged therefrom into the chamber 120 to be thoroughly mixed and then discharged through the openings formed by the portions 125 of the adjacent units. The chamber 122 serving as means for heating the chamber 95 131 through which the gas flows.

The generating pipe 132 may be supported by suitable brackets 133.

With this improved construction, it will be manifest that the cost of manufacture will 100 be materially reduced because when the units which constitute the body portion are being cast or formed, one of the faces of each unit, or both faces, if desired, will be formed with a depressed portion which constitutes a portion of the gas discharge narrow slots, when the units are assembled. It has been customary heretofore in burners of this character to cast the body all in one piece and then saw, mill or cut out the very narrow slots 110 which form the gas discharge outlets. This is a laborious job and necessitates considerable time at a considerable expense. With the present invention all of these objections are obviated.

While the preferred forms of the invention have been herein shown and described, it is to be understood that various changes may be made in the details of construction and in the combination and arrangement of 120 the several parts without departing from the spirit of this invention.

What is claimed as new is:—

1. A hydrocarbon burner embodying a sectional body portion, said body portion 125 embodying individual coöoperating units, each of the units being provided with means whereby, when the units are assembled, two chambers, will be formed, one encompassing the other, and means for detachably secur- 130

ing the units together, there being gas outlet openings leading from the outer chamber.

2. A burner of the character described embodying a sectional body portion, each section constituting an individual unit, and means for detachably securing the units together, there being coöperating openings in the units to form an interior chamber and a chamber encompassing the said interior 10 chamber, and means whereby gas may be supplied to the outermost chamber, the proximate faces of the portions of adjacent units forming the outer walls of the outermost chamber being shaped to form a narrow gas discharge opening leading from the 15 last said chamber.

3. A burner of the character described embodying a sectional body portion, said body embodying complementary units detachably secured together, there being coöperating openings in the units whereby an interior chamber and an encompassing gas chamber will be formed, adjacent unit faces of the portions of the units forming the 25 outer wall of the gas chamber being shaped to form coöperating portions of gas discharge openings leading from the last recited chamber.

4. A burner of the character described 30 embodying a sectional body portion, said body embodying individual units detachably secured together, said units embodying an annular inner portion, radial ribs projecting from the periphery of the said annular portion, and a circumferential flange connecting and encompassing the ribs.

5. A burner of the character described 35 embodying a sectional body portion, said body embodying individual units detachably secured together, said units embodying an annular inner portion, radial ribs projecting from the periphery of the said annular portion, and a circumferential flange connecting and encompassing the ribs, a portion of said flange being shaped to form 45 ribs projecting perpendicularly therefrom, whereby portions of said unit will be held spaced from the proximate face of the next adjacent unit to form therewith a narrow 50 discharge gas outlet.

6. A burner of the character described embodying a sectional body portion, each section constituting an individual unit, said units being detachably secured one adjacent the other, said units embodying an annular inner portion, ribs radiating from the periphery thereof, a circumferential flange connected with the ends of the ribs, and encompassing the said annular portion, 55 whereby an inner chamber will be formed by the annular portions of the units when assembled and the spaces between the ribs will form a chamber exterior of the first said chamber, proximate faces of adjacent 60 units being shaped to form gas discharge 65

outlets leading from the said outer chamber, end members for the units, means for detachably securing the units and end members together, and means for introducing into the said outer chamber the fluid to be burned. 70

7. A burner of the character described embodying a sectional body, said body embodying individual units detachably secured together, provisions whereby the units will coöperate to form within the burner a heating chamber and a gas chamber encompassing the latter, the proximate faces of adjacent units being shaped to form narrow gas discharge outlet openings leading from the 75 gas chamber, a vaporizing chamber disposed adjacent the said body to be impinged by the flame coming from the said outlet openings, and means whereby vapor may be conducted from said vaporizing chamber and discharged into the said gas chamber. 80

8. A burner of the character described embodying a sectional body, said body embodying individual units detachably secured together, provisions whereby the units will coöperate to form within the burner a heating chamber and a gas chamber encompassing the latter, the proximate faces of adjacent units being shaped to form narrow gas discharge outlet openings leading from the 85 said gas chamber, a vaporizing chamber disposed adjacent the said body to be impinged by the flame coming from the said outlet openings, and means whereby vapor may be conducted from said vaporizing chamber and discharged into the gas chamber, the said means embodying an air and gas mixing passage. 90

9. A burner of the character described embodying a sectional body, said body embodying individual units detachably secured 105 one adjacent the other, provisions whereby the units will coöperate to form within the body of the burner a heating chamber and a gas chamber encompassing the latter, end members coöoperating with the said units to 110 form closures for the chambers, securing means for the elements, the proximate faces of adjacent units, and of the units and the respective adjacent end members being shaped to form narrow slots constituting discharge 115 outlets from the gas chamber, and means for introducing into the said gas chamber the gas to be burned, the last recited means embodying means for vaporizing fuel oil.

10. A burner of the character described 120 embodying a sectional body, said body embodying individual units detachably secured one adjacent the other, provisions whereby the units will coöperate to form within the body of the burner a heating 125 chamber and a gas chamber encompassing the latter, end members coöoperating with the said units to form closures for the chambers, securing means for the elements, the proximate faces of adjacent units, and of 130

- the units and the respective adjacent end members being shaped to form narrow slots constituting discharge outlets from the gas chamber, and means for introducing into the said gas chamber the gas to be burned, the last recited means embodying means for vaporizing fuel oil, and an air and gas mixing passage having communication with the said gas chamber.
10. 11. A burner of the character described embodying a sectional body, said body embodying individual units detachably secured together, provisions whereby the units will coöperate to form within the burner a heating chamber and a gas chamber encompassing the latter, the proximate faces of adjacent units being shaped to form narrow gas discharge outlet openings leading from the gas chamber, a vaporizing chamber disposed adjacent the said body to be impinged by the flame coming from the said outlet openings, means whereby vapor may be conducted from said vaporizing chamber and discharged into the said gas chamber, and a priming cup disposed in proximity to and beneath the said vaporizing chamber.
12. A burner of the character described embodying a sectional body, said body embodying individual units detachably secured together, provisions whereby the units will coöperate to form within the body a heating chamber and a gas chamber encompassing the latter, interlocking means on the proximate face of adjacent units, the said proximate faces being also shaped to form narrow gas discharge outlet openings leading from said gas chamber, end members coöperating with the units and forming closures for the said chambers, securing means for the said end members and the units, and means for introducing into the said gas chamber the gas to be burned.
13. A burner of the character described embodying a sectional body, said body embodying individual units detachably secured together, provisions whereby the units will coöperate to form within the body a heating chamber and a gas chamber encompassing the latter, interlocking means on the proximate faces of adjacent units, the said proximate faces being also shaped to form narrow gas discharge outlet openings leading from said gas chamber, end members coöperating with the units and forming closures for the said gas chamber, securing means for the said end members and the units, and means for introducing into the said gas chamber the gas to be burned, the said gas discharge outlet openings extending in a direction circumferentially of the body.
14. A burner of the character described embodying a sectional body, said body embodying individual units detachably secured adjacent each other, provisions whereby the units will coöperate to form within the body a heating chamber and a gas chamber encompassing the latter, interengaging means on the proximate faces of adjacent units for maintaining the units in position, end members coöperating with the units and forming closures for the gas chamber, securing means for the said members and units, the proximate faces of adjacent units and of the units and respective end members being shaped to form extended narrow openings constituting gas discharge outlets from the gas chamber, and means for vaporizing a fluid fuel and introducing the vapor into the said gas chamber, the last recited means embodying a vaporizing pipe through which the fuel passes, said pipe being disposed to extend for considerable distance adjacent the outer face of the body.
15. A burner of the character described embodying a sectional body, said body embodying individual units detachably secured one adjacent the other, provisions whereby the units will coöperate to form a gas chamber within the body, end members coöperating with the units and forming closures for the chamber, securing means for the units and end members, the proximate faces of adjacent units being shaped to form narrow slots constituting gas discharge outlet openings leading from the chamber, said units being also shaped to form when assembled, an interior heating chamber encompassed by the first recited chamber, and against the walls of which interior chamber the gas is directed, and means for introducing gas into the first recited chamber.
16. A burner of the character described embodying a sectional body, said body embodying individual units detachably secured one adjacent the other, provisions whereby the units will coöperate to form a gas chamber within the body, end members coöperating with the units and forming closures for the chamber, securing means for the units and end members, the proximate faces of adjacent units being shaped to form narrow slots constituting gas discharge outlet openings leading from the chamber, said units being also shaped to form when assembled, an interior heating chamber encompassed by the first recited chamber, and against the walls of which interior chamber the gas is directed, a vaporizing pipe arranged adjacent and extending for considerable distance in proximity thereto, and means for conducting the vapor from said vaporizing pipe and discharging the same into the first recited chamber.
17. A burner of the character described embodying a sectional body, said body embodying individual units, interengaging means on the proximate faces of adjacent units for alining the units, and securing means for the units, the said proximate faces being also shaped to form extended narrow

- gas discharge slots therebetween, the said body embodying an interior heating chamber and an encompassing gas chamber and from which gas chamber the said slots discharge. 5
18. A burner of the character described embodying a sectional body, said body embodying individual units, interengaging means on the proximate faces of adjacent units for alining the units, and securing means for the units, one edge of the units having projections and depression therebetween and cooperating with the proximate edge of the next adjacent unit to form a gas discharge opening therebetween, said units being shaped to form an inner heating chamber and an encompassing gas chamber in the wall of which gas chamber the said discharge opening is formed. 10
19. A burner of the character described embodying a sectional body, said body embodying individual units, interengaging means on the proximate faces of adjacent units for alining the units, securing means for the units, the said proximate faces being also shaped to form extended narrow gas discharge slots therebetween, and means for introducing into the body a gas to be discharged through the said slots, said units being shaped to form an inner heating chamber and an encompassing gas chamber in the wall of which gas chamber the said slots are formed. 15
20. A burner of the character described embodying a plurality of individual units detachably secured together, each of said units embodying an annular peripheral portion and an apertured central portion concentrically arranged within and spaced from the first said portion, spaced radial ribs connecting the said portions, end members cooperating with the units to form a chamber between the said portions of the units, interengaging means on the proximate faces 25 of the said annular portions for alining the units, the said proximate faces being also shaped to form narrow slots constituting gas discharge outlets leading from the said chamber, and means for introducing a fluid fuel into the said chamber. 30
21. A burner of the character described embodying a plurality of individual units detachably secured together, each of said units embodying an annular peripheral portion and an apertured central portion concentrically arranged within and spaced from the first said portion, spaced radial ribs connecting the said portions, end members cooperating with the units to form a chamber between the said portions of the units, interengaging means on the proximate faces of the said annular portions for alining the units, the said proximate faces being also shaped to form narrow slots constituting gas discharge outlets leading from the said chamber, and means for vaporizing and introducing fuel into the said chamber, the said apertured portion of the units cooperating to form a heating chamber for the fuel arranged within the first said chamber. 35
22. A burner of the character described embodying a plurality of individual units detachably secured together, each of said units embodying an annular peripheral portion and an apertured central portion concentrically arranged within and spaced from the first said portion, spaced radial ribs connecting the said portions, end members cooperating with the units to form a chamber between the said portions of the units, interengaging means on the proximate faces of the said annular portions for alining the units, the said proximate faces being also shaped to form narrow slots constituting gas discharge outlets leading from the said chamber, and means for vaporizing and introducing fuel into the said chamber, the said apertured portion of the units cooperating to form a heating chamber for the fuel arranged within the first said chamber. 40
23. A burner of the character described embodying a plurality of individual units detachably secured together, each of said units embodying an annular peripheral portion and an apertured central portion concentrically arranged within and spaced from the first said portion, spaced radial ribs connecting the said portions, end members cooperating with the units to form a chamber between the said portions of the units, interengaging means on the proximate faces of the said annular portions for alining the units, the said proximate faces being also shaped to form narrow slots constituting gas discharge outlets leading from the said chamber, and means for vaporizing and introducing fuel into the said chamber, the said apertured portion of the units cooperating to form a heating chamber for the fuel, the said chambers being out of communication with each other. 45
24. A burner of the character described embodying a plurality of individual units detachably secured together to form a hollow body portion, the said units embodying an annular peripheral portion and an apertured central portion concentrically arranged within and spaced for considerable distance from the first said portion, spaced radial ribs connecting the said portions, end members cooperating with the units to form a chamber, interengaging portions on the proximate faces of the respective said portions of the units for alining the same, the proximate faces of the said peripheral portions being shaped to form narrow gas discharging slots, the said apertured portions of the units cooperating to form an inner chamber, and means for vaporizing and conducting fuel through the said inner chamber. 50

- ber without discharging the same into the chamber, and then discharging the vapor into the first said chamber.
25. A burner of the character described embodying a plurality of individual units detachably secured together to form a hollow body portion, the said units embodying an annular peripheral portion and an apertured central portion concentrically arranged within and spaced for considerable distance from the first said portion, spaced radial ribs connecting the said portions, end members coöperating with the units to form a chamber, interengaging portions on the proximate faces of the respective said portions of the units for alining the same, the proximate faces of the said peripheral portions being shaped to form narrow gas discharging slots, the said apertured portions of the units coöperating to form an inner chamber and means for vaporizing and conducting fuel through the said inner chamber without discharging the same into the chamber, and then discharging the vapor into the first said chamber, the said means embodying a vaporizing pipe exterior of the said body and a pipe leading from the vaporizing pipe and extending through the said inner chamber.
30. 26. A burner of the character described embodying a plurality of individual units detachably secured together, each of said units embodying an annular outer portion and an annular inner portion concentrically arranged and spaced from each other, spaced radial ribs connecting said portions, a central unit on each side of which a plurality of units are disposed, said member also embodying spaced concentrically arranged annular portions and spaced radial ribs connecting the portions, a plurality of said units being disposed on each side of said member, end members to form walls for the chamber formed between the said annular portions of the elements, the said inner annular portions coöperating to form a separate chamber out of communication with the first said chamber, there being gas discharge outlets leading from the first recited chamber, vaporizing pipes arranged adjacent the outside of the burner, a pipe connected with the vaporizing pipe and extending through the inner chamber to conduct the fuel therethrough, and means for discharging the vapor from the vaporizing pipe into the first said chamber.
35. 27. A burner of the character described embodying a plurality of individual units detachably secured together, each of said units embodying an annular outer portion and an annular inner portion concentrically arranged and spaced from each other, spaced radial ribs connecting said portions, a central unit on each side of which a plurality of units are disposed, said central unit also embodying spaced concentrically arranged annular portions and radial ribs connecting the portions, a plurality of said units being disposed on each side of said central unit, end members to form walls for the chamber formed between the said annular portions of the elements, the said inner annular portions coöperating to form a separate chamber out of communication with the first said chamber, there being gas discharge outlets leading from the first recited chamber, vaporizing pipes arranged adjacent the outside of the burner, a pipe connected with the vaporizing pipe and extending through the inner chamber to conduct the fuel therethrough, and means for discharging the vapor from the vaporizing pipe into the first said chamber.
40. 28. A burner of the character described embodying a plurality of individual units detachably secured together, each of said units embodying an annular outer portion and an annular inner portion concentrically arranged and spaced from each other, spaced radial ribs connecting said portions, a central unit on each side of which a plurality of units are disposed, said central unit also embodying spaced concentrically arranged annular portions and radial ribs connecting the portions, a plurality of said units being disposed on each side of said central unit, end members to form walls for the chamber formed between the said annular portions of the elements, the said inner annular portions coöperating to form a separate chamber out of communication with the first said chamber, there being gas discharge outlets leading from the first recited chamber, vaporizing pipes arranged adjacent the outside of the burner, a pipe connected with the vaporizing pipe and extending through the inner chamber to conduct the fuel therethrough, and means for discharging the vapor from the vaporizing pipe into the first said chamber.
45. 29. A burner of the character described embodying a plurality of individual units detachably secured together, each of said units embodying an annular outer portion and an annular inner portion concentrically arranged and spaced from each other, spaced radial ribs connecting said portions, a central unit on each side of which a plurality of units are disposed, said central unit also embodying spaced concentrically arranged annular portions and radial ribs connecting the portions, a plurality of said units being disposed on each side of said central unit, end members to form walls for the chamber formed between the said annular portions of the elements, the said inner annular portions coöperating to form a separate chamber out of communication with the first said chamber, there being gas discharge outlets leading from the first recited chamber, vaporizing pipes arranged adjacent the outside of the burner, a pipe connected with the vaporizing pipe and extending through the inner chamber to conduct the fuel therethrough, and means for discharging the vapor from the vaporizing pipe into the first said chamber.

- of the elements, the said inner annular portions coöperating to form a separate chamber out of communication with the first said chamber, there being gas discharge outlets 45
 5 leading from the first recited chamber, vaporizing pipes arranged adjacent the outside of the burner, means for discharging the vapor from the vaporizing pipe into the first said chamber, and supports projecting
 10 from the said central unit and end members for supporting the vaporizing pipe.
 30. A burner of the character described embodying a plurality of individual units detachably secured together, each of said
 15 units embodying an annular outer portion and an annular inner portion concentrically arranged and spaced from each other, spaced radial ribs connecting said portions, a central unit on each side of which a plurality
 20 of units are disposed, said central unit also embodying spaced concentrically arranged annular portions and radial ribs connecting the portions, a plurality of said units being disposed on each side of said central unit.
 25 end members to form walls for the chamber formed between the said annular portions of the elements, the said inner annular portions coöperating to form a separate chamber out of communication with the first said
 30 chamber, there being gas discharge outlets leading from the first recited chamber, vaporizing pipes arranged adjacent the outside of the burner, a pipe connected with the vaporizing pipe and extending through the
 35 inner chamber to conduct the fuel therethrough, means for discharging the vapor from the vaporizing pipe into the first said chamber, and interengaging means on the proximate faces of adjacent unit elements
 40 for maintaining the latter in position.
 31. A burner of the character described embodying a vapor chamber having ends provided with openings therethrough, and an inlet opening intermediate the ends of
 the chambers, the wall of said chamber adjacent the inlet being imperforate except for said inlet opening, for a distance not less than the diameter of said opening, and being provided with outlet slots on each side of the said imperforate portion, a vaporizing 50
 pipe passing through said chamber and through the openings in the ends of the chamber and supported by the said ends, said pipe being of a diameter considerably smaller than the chamber, means for supplying to the pipe fuel to be vaporized, and means for directing the vapor from said pipe into the chamber exterior of the pipe and through the said inlet opening.
 32. A burner of the character described 60
 embodying a vapor chamber having ends provided with openings therethrough, and an inlet opening intermediate the ends of the chamber, the wall of said chamber adjacent the inlet being imperforate except for 65
 said inlet opening, for a distance not less than the diameter of said opening, and being provided with outlet slots on each side of the said imperforate portion, a vaporizing pipe passing through said chamber and through the openings in the ends of the chamber, members encompassing the said pipe and engaging the ends of the chamber for holding the pipe in position, said pipe being of a diameter considerably smaller 70
 than the chamber, means for supplying to the pipe fuel to be vaporized, and means for directing the vapor from said pipe into the chamber exterior of the pipe and through 75
 the said inlet opening.
 80

In testimony whereof I have signed my name to this specification, in the presence of two subscribing witnesses, on this 18th day of October, A. D. 1917.

FOREST V. DETWILER.
